FUSE LINK

Filed May 19, 1930

UNITED STATES PATENT OFFICE

LESTER PIERCE BOLL, OF UNIVERSITY CITY, MISSOURI, ASSIGNOR TO W. N. MATHEWS CORPORATION, OF ST. LOUIS, MISSOURI, A CORPORATION OF MISSOURI

FUSE LINK

Application filed May 19, 1930. Serial No. 453,818.

This invention relates to fuse links, and with regard to certain more specific features, to a new and improved fuse link for use in expulsion types of fuse cartridges.

5 Among the several objects of the invention may be noted the provision of a fuse link wherein a combination of a weight and a spring insures a quick opening of the circuit under all conditions of overload; the provision of a fuse link which, although new, may be used with older types of fuse cartridges, thereby preventing equipment already installed from becoming obsolete; the provision of a fuse link which gives a positive 10 indication when the fuse is blown; the provision of a fuse which advantageously uses expulsion gases engendered when a fuse is blown by short circuiting, but which does not depend only upon these engendered gases 15 for a quick break; and the provision of a fuse link which is simple, economical, and easily manufactured and installed. Other objects will be in part obvious and in part pointed out hereinafter.

20 25 The invention accordingly comprises the elements and combinations of elements, features of construction, and arrangements of parts which will be exemplified in the structure hereinafter described, and the scope 30 of the application of which will be indicated in the following claims.

In the accompanying drawings, in which is illustrated one of various possible embodiments of the invention,

35 Fig. 1 is a typical installation of an expulsion type of fuse wherein the new and improved fuse link is employed;

40 Fig. 2 is a longitudinal cross section of a typical fuse cartridge wherein the new and improved fuse link is connected; and,

45 Fig. 3 is an elevation of the new and improved fuse link.

Similar reference characters indicate corresponding parts throughout the several 50 views of the drawings.

55 Referring now more particularly to Fig 1, there is illustrated at numeral 1 a supporting bracket to which are attached by means of shackle bolts 5 insulators 3. The insulators 5 support arms 7 which have bolted

thereto pairs of terminal spring clips 9. These clips are of a class which engage two sides of a connecting member by means of a plurality of spring engaging fingers.

Bolted between each arm 7 and its respective set of clips 9 is a terminal piece 11 to which may be connected leads 13.

Between the lowermost set of clips 9 and its respective arm 7 is held a hinge member 15. This hinge member 15 is provided with a flat portion 17 adapted to flatly engage with arm 7. The hinge also comprises a pair of downwardly hooked arms 23 extending from said flat portion.

The fuse cartridge 25 comprises a fuse link 65 27 which is adapted to electrically connect the spring terminal clips 9. This fuse is removably connected to an upper metallic block 29 which is provided with proper parallel faces 43 for engaging the upper resilient spring 70 clips 9. A stud 31 removably retains the fuse in position with said upper block 29. This block is also provided with a suitable bridge portion 33 which may be hooked by the end of a suitable insulating tool so that the operator 75 may draw the block 29 from the upper clip 9 without physically engaging current carrying members. The upper metallic block 29 is held to the insulating cartridge tube 35 by means of a set screw 37.

80 Toward the lower end of cartridge tube 35 there is held by means of a suitable set screw 39 a hollow terminal hinge block 41. This block 41 comprises a hollow form having substantially flat parallel faces 43 for the purpose of engaging the lower resilient spring 85 clips 9. Gudgeons 45 sidewardly extend from these parallel faces for the purpose of hingedly engaging the hinge member 15 at the hook portion of the arms 23. On one 90 face of the block 41 there is provided a tapped surface adapted to receive a set screw 47 for holding the lower end of fuse 27.

95 It is to be understood that the foregoing disclosure is exemplary only and is but an illustration of a typical installation which serves to show clearly the use of my invention. A more detailed description of the switch hanger and fuse cartridge may be obtained by referring to United States Patent

1,704,961, issued to Theodore Birkenmaier, dated March 12, 1929.

The portion of the fuse link 27 which is adapted to be blown during overloads is preferably composed of two lengths of nichrome wire 49 and 51 soldered together as shown at numeral 53. The size of the nichrome wires 49 and 51, the amount and kind of solder used, and the overlap in making the joint 53 may so be adjusted and/or chosen that this portion of the fuse link will carry normal load currents without any appreciable heating and when an overload is encountered, the link will melt or blow at the joint 53. Nichrome wire possesses the special advantage that it does not stretch by heating and the desirability of this feature will be apparent hereinafter.

To the upper end of the fuse link there is soldered or otherwise affixed a lug 55 adapted to be compressingly held within the fuse cartridge 25 by means of stud 31 (see Fig. 1).

To the lower end of the length 51 there is soldered or otherwise affixed a length of copper or other wire 57. This wire should be of such composition and size that it will not stretch during normal load currents. For purposes of economy, this wire may conveniently be copper wire but should be of a larger cross-sectional area than the nichrome wires 49 and 51 so that it will carry the normal currents without any appreciable heating and/or stretching.

On wire 57 there is tightly affixed a weight 59. Weight 59 is preferably made of lead and preferably, though not necessarily, bullet-shaped, and should be small enough to easily move within cartridge tube 25 but should be large enough in diameter to present an appreciable surface which will afford a driving action to the slug when gases are engendered by the fuse blowing under a heavy overload.

To the lower end of wire 57 there is soldered or otherwise affixed a helical spring 61. This spring 61 may conveniently be made of spring brass or phosphor bronze wire and should be so proportioned that it will not heat and stretch appreciably under normal load currents. It should furthermore be so proportioned that the fuse link may be given an appreciable longitudinal stress when connected within fuse cartridges 25.

To the lower end of spring 61 there is soldered or otherwise affixed a length of wire 63 which may be of the same composition and size as wire 57. The lower end of this wire 63, after making a hairpin turn at the bottom of the tube, engages with set screw 47 and completes the circuit thereby between the sets of clips 9 by means of fuse link 27.

When inserting this fuse link within its cartridge, the upper terminal or lug 55 is first secured in place by means of stud 31. A tension is then applied to the fuse link so

as to appreciably stretch the spring 61 (it is shown in a stretched position in Fig. 2) and with the spring in this stretched position the length of wire 63 is tightly secured in place by means of the set screw 47.

Under normal conditions of operation the currents carried by the fuse link do not cause any additional stretching of this link so that the link is always under an appreciable tension. As the load increases and the "blowout" value is approached, the link still remains in its originally stressed position, because the component parts have been so chosen, as pointed out hereinbefore, that currents up to and including the "blowout" value of current will not cause any appreciable stretching of the component parts of the link.

Assuming first that the load current gradually increases to the "blowout" value, it is clear that when the joint 53 is melted and broken by this value of current, the spring 61 will quickly pull the adjoining ends of wires 49 and 51 apart and provide thereby a relatively quick and large opening for the break. The length of this break would, in the absence of the slug or weight 59, not be appreciably greater than the distance which the spring 61 has been stretched at the time of installing the link. It will be seen however, that after the spring has pulled apart the joint 53, then the dead weight of the slug 59 and the kinetic energy imparted thereto by the spring 61 result in the initial gap being widened, the parts of the link below point 53 dropping entirely from the cartridge tube. The weight in effect prevents the fuse link from being supported in arcing position by the sides of the tube, said weight clearing the tube after the spring has effected a sudden break.

It is clear that the provision of the weight in combination with the spring affords a longer break than would be provided by the spring alone. It is also clear that a quicker break is provided than what would be obtained if the weight alone were used, especially on so-called "dragging" overloads.

For short circuits or sudden application of heavy overload, an even quicker break is effected. As has been pointed out hereinbefore, the weight 59 is large enough in cross-sectional area to afford an appreciable surface against which press the gases engendered by the sudden gasification of the fuse, thus discharging the weight from the end of the tube. It is to be understood that the upper end of the cartridge tube is closed tight and the lower end is open. Although this explosive force exerted upon weight 59 by the engendered gases serves to provide a quick break, it is clear that this action is supplementary to the combined effect of the weight and the spring. Upon a sudden overload all three of these causes contribute to improved

action; upon a "dragging" overload, the spring and the weight are effective.

It is thus seen that a quick and long break is effected under any condition of overload.

5 It is clear that the provision of such a long and quick break within a closed tube has distinct advantages. As has been pointed out, the enclosed cartridge tube in combination with a weight on a fuse link provides, beside 10 the other advantages enumerated, an explosive type of fuse especially effective at short circuits or quick overloads. The enclosure for the fuse link also provides an element of safety not found in the open type of fuse.

15 As shown, the fuse is preferably mounted in an upright position. Mounted in such a position, the effect of the spring and weight becomes more effective, as is also the action of the engendered gases, if any.

20 Inasmuch as the weight and spring hang out of the open end of the tube after the fuse has blown, there is provided a positive indication that the fuse is blown. With such fuses mounted at substantial heights, this is 25 a distinct advantage because a lineman on the ground can easily determine which of a number of fuses is blown before climbing up to insert new fuse links.

By the term "soldered joint" is meant 30 herein, one which effects a juncture between different pieces by an applied melted material which subsequently hardens.

In view of the above, it will be seen that 35 the several objects of the invention are achieved and other advantageous results attained.

40 As many changes could be made in carrying out the above constructions without departing from the scope of the invention, it is intended that all matter contained in the above description or shown in the accompanying drawings shall be interpreted as illustrative and not in a limiting sense.

I claim:

45 1. A fuse link comprising lengths of wire, a joint connecting said lengths, a weight on one of said lengths, and a spring in said length containing said weight, said link being adapted to melt at said soldered joint 50 upon overload.

55 2. A fuse link comprising lengths of wire, a joint connecting said lengths, a weight on one of said lengths, and a spring in said length containing said weight, said joint being positioned above the weight and the spring.

60 3. In a fuse cartridge means for quickly providing a long break comprising a weight, a spring and a length of wire having a fusible point, said weight and said spring being adapted to be expelled from said fuse cartridge when said joint is blown.

65 4. A fuse link comprising lengths of wire, a joint connecting said lengths, a weight on

one of said lengths, and a spring in said length containing said weight.

5 In a fuse cartridge, a fuse link comprising lengths of wire, a soldered joint connecting said lengths, a weight on one of said lengths, a spring in said length containing said weight, said link being adapted to be held within said cartridge in a strained condition and adapted to move out of said cartridge when said link blows. 70

6 In a fuse cartridge, a fuse link comprising lengths of wire, a soldered joint connecting said lengths, a weight on one of said lengths, a spring in said length containing said weight, said weight having an area 80 adapted to offer appreciable resistance to engendered gases when said fuse blows suddenly, said gases expelling said weight from said cartridge. 75

7. A fuse link comprising a length of wire, 85 a calibrated fusible portion therein, a weight on said link, a spring inserted in said link, said spring being adapted to permit of the tensioning of said link when in use and adapted to impart movement to said weight when 90 said fusible portion blows.

8. In a fuse switch, means for providing a quick and long break under all conditions of overload, comprising a fuse cartridge closed at one end and open at the other, said cartridge containing a tensioned and weighted 95 fuse link.

9. In a fuse cartridge, a fuse link comprising lengths of wire, a soldered joint connecting said lengths, a weight on one of said lengths, a spring in said length containing said weight, said link being adapted to be held within said cartridge in a strained condition and adapted to move out of said cartridge when said link blows, the spring causing sudden initial movement to form an incipient gap, said weight continuing said movement to widen the gap. 100

10. A switch cartridge comprising a tube having a lower opening and closed top, a fuse link therein connected at the top and outside of said lower opening and having a hairpin turn at said lower opening, a meltable portion in said link near said top and a strained spring and a weight associated with said link between the meltable portion and said lower opening. 110

11. A switch cartridge comprising a tube having a lower opening and closed top, a fuse link therein connected at the top and having a hairpin turn at said lower opening, means for fastening said link outside of said opening and a meltable portion in said link near said top and a strained spring and a weight associated with said link between the meltable portion and said lower fastening means. 120

12. A switch cartridge comprising a tube having a lower opening and closed top, a fuse link therein connected at the top, means for

fastening said link outside of said opening and a melttable portion in said link near said top and a strained spring and a weight associated with said link between the melttable portion and said lower fastening means.

5 13. In a fuse a fuse link, means for uprightly placing said link, an upper melttable portion in said link and a strained spring and weight connected therewith below the melt-

10 able portion.

14. In a fuse a fuse link, means for uprightly placing said link, an upper melttable portion in said link and a strained spring and weight connected therewith below the melt-

15 able portion, said spring being below the weight.

16. In a fuse a fuse link, means for uprightly placing said link, an upper melttable portion in said link and a strained spring and weight connected therewith below the melt-

20 able portion said spring being below the weight and a tube surrounding those portions of the link carrying the melttable portion, weight and spring.

25 15. In testimony whereof, I have signed my name to this specification this 16th day of May, 1930.

LESTER PIERCE BOLL.
